LOCKING MEANS FOR WORKHOLDERS OR JIGS

Application filed February 12, 1931. Serial No. 515,390.

The present invention pertains to a novel frictional locking mechanism of a type particularly adapted for use in combination with various types of work holders such as quick acting vises or jigs.

The primary object of the present invention is to devise a locking mechanism which when mounted upon the operating shaft of a quick acting vise or jig serves as means for 10 rotating said shaft to exert clamping pressure upon the work clamping head, said mechanism comprising parts which co-act in a manner to permit a predetermined amount of pressure to be exerted upon said shaft and 15 clamping head and then serving to frictionally prevent rotation of said shaft either by pressure of the operating handle or back pressure exerted by the clamping head upon the shaft.

Another object of the present invention is to devise a locking mechanism which may be 20 constructed as a separate unit applicable to any shaft wherein it is desired to rotate the same until a predetermined pressure is 25 reached, said mechanism serving as a locking means for holding said shaft at any stage of revolution when the predetermined pressure is reached. The device serves as a means for rotating the shaft in either direction but 30 prevents an excessive amount of rotative pressure from being exerted upon said shaft inasmuch as the pressure after reaching a certain degree only tends to more securely lock the device rather than rotate the shaft.

With the above and other ends in view the invention consists in matters hereinafter set forth and more particularly pointed out in the appended claims, reference being had to the accompanying drawing, in which

Figure 1 is a transverse cross sectional view through the present locking mechanism, the view being taken substantially on the line A—A of Fig. 2;

Fig. 2 is a longitudinal cross sectional view taken on the line B—B of Fig. 1, and

Fig. 3 is a side elevation of a conventional jig illustrating the attachment of the present device thereto.

Like characters of reference are employed

throughout to designate the corresponding parts.

The numeral 1 indicates the supporting or outer casing having holes 2 through which bolts are passed to secure the casing to the side wall of the jig 14 or any other similar holding device. The casing 1 is provided with a circular bore 1' through which the jig operating shaft 7 projects.

Loosely surrounding the portion of the 60 shaft 7 which projects outwardly through the casing 1 is an actuating member 5, preferably formed of angular shape such as a hexagonal nut to receive an operating handle or wrench 12. The actuating member 5 is 65 retained from slipping off the shaft 7 by the washer 11 which is secured to the end of the shaft by means of a screw 8, screwthreaded into a suitable bore provided in said shaft.

The outside diameter of the actuating 70 member 5 is greater than the diameter of the bore 1' and therefore covers the end of the same as clearly illustrated in Fig. 2 of the drawing. Formed on the inside face of the actuating member is a flat walled projection 75 5' which projects into the bore 1' for a purpose which will become apparent as the description progresses.

A block 6 is mounted upon the shaft 7 within the bore 1' and is keyed as at 9 to rotate 80 therewith, the block having flattened walls 6'. Resting against the flat faces 6' are wedges 4 which serve to normally hold a pair of segments 3 in contact with the wall of the bore 1', the segments having their outer walls 85 curved with the same radius as the bore 1'.

The wedges 4 are provided with recesses 4' into which the projection 5' on the actuating member projects, the recess being formed large enough to provide a slight clearance. In the segments 3 are formed recesses 3' constructed to provide a greater clearance on either side of the flattened projection 5' than is provided in the wedge. The projection 5' is bored as at 10' and springs 10 are 95 placed in said bores in a manner to project outwardly therefrom and contact with one of the walls of the recess 3'.

In operation it is desired to rotate the shaft by applying pressure upon the handle 12. 100

The rotation of the handle rotates the actuating member 5 and the side walls of the projection 5' rotates the wedges 4 and segments 3, the wedges causing the block 6 to be rotated and because it is keyed to the shaft the latter rotates also. It will be noted however that the rotation is imparted to the segments by the spring 10 and therefore when the resistance on the shaft 7 becomes greater than the pressure of the spring the latter is compressed and the rotative pressure on the actuating member is then imparted upon the side walls of the recesses 4' in the wedges which are thereby moved in a manner to force the segments outwardly against the wall of the bore 1' and thus lock the segments, wedges, block 6 and the shaft 7 against further rotation.

In order to release the locking mechanism pressure is exerted upon the handle 12 in the opposite direction and the projection 5' engages the opposite side wall of the recesses 4' causing the wedges to be moved outwardly in a manner permitting the outward or locking pressure of the wedges against the segments to be released.

The direction in which the small ends of the wedges are pointed governs the direction in which the operating handle must be turned in order to cause the locking edges. It becomes apparent, therefore, that the device is adaptable to either clockwise or contra-clockwise turning operating handles by merely reversing the direction of the small ends of the wedges.

Although a specific embodiment of the present invention has been illustrated and described it is to be understood that various changes may be made in the details of construction without departing from the spirit 40 of the invention as defined in the appended claims, and such changes are contemplated.

What we claim is:

1. The combination with a shaft upon which back pressure is exerted, of an actuating member freely mounted upon said shaft, a member non-rotatably mounted upon said shaft, a stationary casing mounted to surround said shaft, segments mounted in said casing, wedges interposed between said segments and said non-rotatable member, said wedges and segments being engaged by said actuating member in a manner whereby excessive rotative pressure on said actuating member causes said wedges to force said segments tightly in contact with said casing when the resistance against rotation on said shaft reaches a certain degree.

2. The combination with a shaft upon which back pressure is exerted, of a circular fixed casing surrounding an end portion of said shaft, a block secured to said shaft to rotate therewith, wedges contacting with the sides of said block, segments interposed between said wedges and the wall of said casing, and an actuating member loosely mount-

ed upon said shaft and adapted to engage said wedges and segments to impart rotation to said block and thereby rotate said shaft.

3. The combination with a shaft upon which back pressure is exerted, of a stationary casing surrounding the end of said shaft, a flat sided member mounted upon said shaft to rotate therewith, wedges contacting with said flat sided member, segments contacting with said wedges and the inner wall of said casing, and an actuating member projecting into recesses formed in said wedges and segments, said actuating member having springs mounted therein to engage said segments whereby rotation of said actuating member causes rotation of said segments, wedges, flat-sided member and shaft.

4. The combination with a shaft upon which back pressure is exerted, of a stationary casing surrounding the end of said shaft, a flat sided member mounted upon said shaft to rotate therewith, wedges contacting with said flat sided member, segments contacting with said wedges and the inner wall of said casing, recesses formed in said segments of greater width of said first named recesses, an actuating member projecting into said recesses in a manner permitting lost motion before engaging the side walls of said recess to impart rotation from said actuating member to said segments, wedges, flat sided member and shaft, and springs carried by said actuating member to engage said segments in a manner whereby excessive back pressure on said shaft causes said springs to be compressed and causes said actuating member to move said wedges in a manner to force said segments outwardly into contact with said stationary casing.

5. The combination with a rotatable shaft upon which back pressure is exerted, of a casing having a circular bore non-rotatably secured relative to said casing, an actuating member mounted on said shaft to rotate freely thereon and having projections extending into said circular bore, segments mounted in said circular bore, a block keyed to said shaft to rotate therewith, wedges interposed between said segments and said block, recesses formed in said wedges to receive the projecting portion of said actuating member, recesses formed in said segments of greater width than said first named recesses to receive the projecting portion of said actuating member, and compressed springs mounted in bores in said projection on the actuating member to engage the side walls of the recess in said segments when said projection engages the side walls of the recesses in said wedges.

6. The combination with a shaft upon which back pressure is exerted, a fixed circular casing supported concentric with said shaft, a member fixed on said shaft within said casing to rotate therewith, wedges in

6 said casing between the wall thereof and the sides of said member on said shaft, segments interposed between said wedges and casing wall, an actuating member loosely mounted upon said shaft, means on said actuating member to engage said wedges and positively move the same, and yielding means on said actuating member to move said segments.

10 In testimony whereof we affix our signatures.
